METHOD OF DYEING ARTICLES

Gabriel Lowenstein, New York, N. Y., assignor to
 Fred Fear & Company, Brooklyn, N. Y., a corporation of New York

Application June 6, 1934, Serial No. 729,182

5 Claims. (Cl. 41—33)

This invention relates to a novel method of dyeing articles such as eggs and the like.

One of the objects of this invention is the creation of a new method of dyeing articles to create novel and picturesque dyed articles.

5 A more specific object of this invention is to provide a novel method of dyeing eggs to yield artistic effects thereon.

A still further object of this invention is the 10 provision of a novel method of dyeing eggs to create crazy patch-quilt and rainbow designs thereon in different colors.

A still further object of this invention is to 15 provide an improvement in the method of dyeing eggs and the like disclosed in Patent No. 1,952,612 to Edward Sherwood.

Various other objects than those heretofore recited will appear more fully hereinafter and from the details thereof, illustrated in the accompanying drawing.

20 Figure 1 is a container in which the pieces of dye paper has created a colored dyed solution;

Fig. 2 shows a container in which a different 25 piece of dye paper has created a different color dye solution;

Fig. 3 shows a container in which the dye paper has been cut in the form of an animal and from which a still different color dye solution 30 has been prepared;

Fig. 4 shows different dye papers spread upon and between the wrapping elements by the aid of which they are applied to articles such as Easter eggs;

35 Fig. 5 shows such wrapping element being wrapped about an egg; and

Fig. 6 shows the finally dyed egg.

The invention hereinafter disclosed recites in the combination of steps and sequence of steps, 40 all as will be more fully hereinafter disclosed.

The general purpose of this invention is to provide a method which is an improvement upon that of the above noted patent and by means of which eggs and other articles may be colored 45 and dyed and for a decorative effect impressed upon the surface thereof without blurring.

In the art of egg dyeing to produce colored Easter eggs, numerous attempts in addition to that disclosed in the above numbered patent, 50 have been made to produce artistic, pleasing and picturesque colored designs on the egg surface. The various dyes and method of using the same have been difficult of operation and productive of but poorly dyed eggs. While it has 55 always been possible to secure a solid dye by

dipping eggs into a fluid of a given color, much difficulty has been encountered in depositing upon the surface of the egg, a design made of a multiplicity of interspersed colors to produce an artistic effect. It is the purpose of this invention to provide a method of egg dyeing by a simple series of steps, utilizing easily obtainable dyes in a manner which is an improvement upon the method of the above numbered patent.

There is now on the market an egg dye consisting of a plurality of fibrous paper sheets having different colors impregnated in respective sheets, one of said sheets being of solid yellow, and another of solid red, etc. Sheets of this character may, of course, be used for a solid dye 65 on the surface of an egg or like article. Such sheets have been used by dipping the same into water until the coloring matter with which they are impregnated is dissolved into the water.

The fibrous dye impregnated sheets 1—2 or 75 pieces thereof are immersed in cold, luke-warm or hot water in different glasses 3 so as to produce solid color solutions 4, 5, 6 in each glass. With these solutions it is possible to first dye 70 a number of eggs with solid colors and then dip them into different solutions to provide a surface of various colors or shades as disclosed in the above mentioned patent.

A variegated surface may, however, be more effectively procured by taking sheets of dye impregnated paper 1—2 and cutting them into narrow strips to produce the rainbow design or into various geometrical shapes or shapes simulating animals and the like, to produce the crazy-patch-quilt design. The cut pieces 7—12 are then 85 placed on a damp sheet of paper or other fibrous material or upon a piece of muslin, or other woven or knitted fabric 8, as indicated in Fig. 4. For the rainbow design the strips are laid side by side in any desired color combination over a 90 sufficient area to envelope an egg when wrapped around it or the cut pieces are laid over a sufficient area in any desired design and color combination for the crazy-patch-quilt design.

These pieces are then overlaid by a second 100 sheet 18 of fibrous material such as paper, or a knitted or woven fabric such as muslin which has been moistened so as to be sandwiched therebetween. The sheets 8 and 18 should be dipped in water and then squeezed free of excess 10 water. If too much water is used the colors will run and if the sheets 8 and 18 are not wet enough, the colors will not transfer well to the egg.

The egg or other article to be dyed is then en- 11

closed within the overlying sheets 8 and 18 and subjected to pressure as by squeezing or rolling in the hands as illustrated in Figure 5. It is apparent, that in accordance with this method either eggs which have not been treated at all, or eggs to which a solid color or mixture thereof have been applied may thus be wrapped and squeezed as illustrated in Figure 5. I have found that by this method the designs or shapes of the various pieces 7 and 12 will be impressed upon the egg surface by the dye therein passing through the moist sheet 8 and 18, depending upon which sheet is next to the egg.

There are three important advantages of this improvement in the method of dyeing eggs and the like. I have discovered by interposing the dyed pieces 7 and 12 between the moist layers 8 and 18 that the designs and colors were quickly and accurately transferred to the egg surface and the very important advantage is secured of preventing the pieces 7 and 12 from sticking to the egg surface as the hand is opened and the egg removed from the wrapping. Without this improvement it has been found that the pieces 7 and 12 have a tendency to stick to the egg surface and when removed to blur the design or shape of the pieces as impressed on the egg surface. Furthermore, it is possible to color several eggs with the same sheets by successive applications.

The finished egg 10 has its surface 11 which may or may not have a solid color thereon decorated with random distribution by a plurality of different colored designs having different shapes as illustrated at 7^a and 12^a in Figure 6. It will be apparent that by varying the shape of the piece of varied colored pieces, any desired design may be obtained ranging from what is popularly known as a crazy patch-quilt or patch-work design, to carefully worked out artistic design. This feature is illustrated in the drawing by the animal shapes 12. In this respect not only is the shape of the particular piece of

dyed paper of importance, but also the relative locations of the different pieces of paper of different colors relative to each other.

Having now set forth the object and nature of my invention and having described the principles of the process, what I claim, as new and useful, and of my own invention, and what I desire to secure by United States Letters Patent is:

1. As a new method of dyeing articles, the steps of interposing pieces of dye impregnated fibrous material between layers of moistened sheets and wrapping and pressing the article to be dyed in the moistened sheets.

2. The method of dyeing articles which comprises arranging a plurality of variously color impregnated pieces of moistened fibrous material between two sheets of damp fabric and wrapping and pressing the article to be dyed within said sheets.

3. A method of dyeing articles which comprises the steps of interposing one or more pieces of color impregnated material between two sheets of moistened fibrous material, wrapping the article to be dyed in said sheets and subjecting the wrapped article to rolling pressure.

4. A method of dyeing articles which comprises the steps of interposing variously shaped color impregnated pieces of material between a pair of moistened sheets of fabric, wrapping the article to be dyed in the sheets so as to contact one of them and subjecting the wrapped article to pressure to transfer the shape and color of the dyed pieces to the surface of the article.

5. A method of dyeing articles which comprises the steps of arranging in any desired design and color, combination color impregnated pieces of material between a pair of moistened pieces of fabric wrapping the article to be dyed in the sheets so as to contact one of them and subjecting the wrapped articles to pressure to transfer the shape and color of the dyed pieces to the surface of the article.
